ADJUSTABLE HIGHCHAIR

Ralph H. Thatcher, Claremont, Calif.

Application July 19, 1954, Serial No. 444,109

14 Claims. (Cl. 155—115)

This invention relates to a new and improved adjustable highchair. Reference is made to my co-pending patent application Ser. No. 214,867, filed March 10, 1951 for adjustable highchair, now Patent No. 2,691,411, granted October 12, 1954. The present invention has particular application to a highchair which may be adjusted for the size of the occupant so that the child is correctly and comfortably seated. The invention is important in providing means for adjusting the chair as a child grows or for use in restaurants and the like where children of different ages may occupy the chair.

In prior adjustable chairs it has been the practice to provide separately adjustable backrests, armrests, seats, or footrests, or combinations of the foregoing adjustments. In my prior application I disclosed means whereby the backrest was moved forwardly and rearwardly as the footrest was raised and lowered. The present invention provides a construction whereby with a single adjustment, the seat may be slid rearwardly and forwardly relative to the stationary frame and backrest as the footrest is elevated or depressed. The sliding movement of the seat and the elevation of the footrest are in a definite relationship which follows the normal growth pattern of an infant. The movement of the adjustable parts is inter-related by linkages to provide proper support as the body and limbs of the child grow at any stage of development.

It is an important feature of the present invention that provision is made for comfortably seating the child during meal, play or rest periods so that his physical and mental development will not be hindered by a sense of physical discomfort or instability. Accordingly, the present invention eliminates the use of cushions and books and other devices which have frequently been employed in order to adjust conventional highchairs to children of different sizes and which frequently become displaced.

This invention provides a simple adjustment of the footrest which simultaneously and automatically adjusts the position of the seat relative to the frame and backrest in such manner as to quickly, safely and comfortably accommodate an occupant through a wide range of ages and sizes.

The chair is simple in construction, has a minimum of moving parts and is light in weight by reason of its tubular metal construction and presents a modern, streamlined appearance. The chair may be easily cleaned, an important advantage in infants' chairs.

One of the most important objects of the present invention is the provision of a highchair which adjusts for rapidly growing children and does not require the use of pillows or other compensating devices to accommodate the chair to the growth of the child, thereby encouraging a general psychological improvement in the attitude of the child toward meals.

Still another object of the present invention is the facility with which it may be adapted to use in restaurants where, by a very simple adjustment of the position

2

of the footrest the chair may be adjusted for various different sizes of infants.

Other objects of the present invention will become apparent upon reading the following specification and referring to the accompanying drawings in which similar characters of reference represent corresponding parts in each of the several views.

In the drawings:

Fig. 1 is a side elevation of a highchair illustrating the maximum and minimum adjustment positions, in solid and dot-and-dash lines, respectively.

Fig. 2 is a front elevation of the structure of Fig. 1.

Fig. 3 is a fragmentary sectional view taken substantially along the line 3—3 of Fig. 1.

Fig. 4 is a fragmentary sectional view showing the means whereby the footrest is locked into position relative to the legs of the frame.

Fig. 5 is a side elevation, similar to Fig. 1, of a modified chair.

Fig. 6 is a front elevation of the structure of Fig. 5.

Fig. 7 is a side elevation, similar to Fig. 1, of still another modification of the invention.

Fig. 8 is a front elevation of the structure of Fig. 7.

Fig. 9 is a side elevation of still another modification of the invention.

As shown in Figs 1 and 2, the present invention comprises a stationary frame having front and rear legs, a backrest fixed to the frame and an armrest. The frame is made up of three major members formed of tubing. The main frame member 11 is bent in U shape in front elevation and an elongated S shape in side elevation, providing on each side of the chair a front leg 12 having a curved upper portion 13, horizontal seat mounting portion 14 above the curved portion and a vertical portion 16 above the horizontal portion which supports the backrest 17. The tube is bent in a horizontal stretch 18 across the top of the backrest and down on the other side in a complementary shape. On either side of the chair is a rear leg 19 which extends diagonally upward and is joined to the main frame member by a rivet 21, the tubing being bent outward in offsets 22 to clear the intersection with the main frame member 11. The upper ends of the rear legs 19 are joined to horizontal armrests 23, the rear ends of which are welded to vertical stretches 16 of the main frame so that the five members 11, 19 and 23 comprise a rigid unit. It will be noted that the lower ends of the legs 12 and 19 are flared outwardly to prevent tipping.

The seat 26, which in the present instance is horizontally slideable, is provided with members 27 on either side edge having horizontal slots 28 and enlarged recesses 29 within, which comprise trackways. Rivets 21 are formed with enlarged heads 32 on their inner ends which fit inside the slots 28 and are held within the trackways 29. Second rivets 33 passing through the forward end of the horizontal portion 14 of the main frame member 11 likewise have enlarged heads 32 which fit within the trackways 28. Rivets 21 and 23 are substantially in horizontal alignment so that the seat 26 is supported and may slide horizontally.

A footrest 36 extending between the front legs 12 is pivotally connected by pins 37 to levers 38 on either side of the chair, the opposite ends of the levers 38 being pivotally connected by means of transverse rod 39 to the rear legs 19. Levers 38, as shown in Fig. 1 are bent angularly upwardly and at the apex 41 of the angle are connected by transverse rod 42 to the lower ends of links 43, the upper ends of the links 43 being pivotally connected to ears 44 depending from the forward end of the seat 26.

As has been stated, the front legs of the chair are curved at 13 and the center of this curvature is rod 39.

Thus, as the footrest 36 is swung upwardly from the solid line position of Fig. 1 to the dotted line position, links 43 are pushed rearwardly, which accordingly slides the seat 26 rearwardly relative to the frame and backrest. The relationship is such that when the footrest 36 is elevated to accommodate a small child, the front edge of the seat 26 is closest to the backrest 17. On the other hand, when the footrest 36 is lowered to accommodate the longer legs of a larger child, the front edge of the seat is slid forwardly correspondingly.

Various means may be employed to lock the footrest in position. As shown in the accompanying drawings, a series of spaced holes 46 is formed on the inside of the curved portion of the legs. Elongated pins 37 which connect levers 38 to the footrest are held by depending apertured brackets 47. Helical springs 48 surrounding pins 37 are interposed between inner brackets 47 and collars 49 fixed on pins 37; thus biasing the pins outwardly. Finger holds 51 on the inner ends of the pins 37, located in close proximity, are employed to retract the pins from the holes 46 when adjustment is required.

Thus, in operation when it is desired to adjust the chair for a different size infant, the finger holds 51 are squeezed together, thereby retracting the outer ends of the pins 37 from the holes 46 in the front legs. The footrest is then raised to the desired position and the finger holds released, allowing the pins to seat in the corresponding new holes in the front legs. As the footrest is elevated or depressed, the seat 26 is moved rearward or forward and hence proper adjustment of the depth of seat for the position of the footrest is automatically accomplished.

In Figs. 5 and 6 a modified construction is employed. It will be understood that the frame of Figs. 5 and 6 may be made similar to that of Fig. 1 if desired, and that an armrest may be employed. In any of the modifications illustrated herein, conventional highchair trays (not shown) may be installed.

In the particular embodiment of the frame shown in Figs. 5 and 6 the front legs 56 are separate pieces of tubing and are curved upwardly rearwardly and welded to the rear legs 57. The rear legs are welded to backrest 58 so that the backrest, rear legs and front legs form a rigid unit. Inwardly projecting, horizontally aligned studs 59 on the upper ends of the front legs have enlarged heads 61 on their inner ends similar to heads 32 which fit within slots 62 on the side edges 63 of horizontal seat member 64. Thus, seat member 64 may slide forwardly and rearwardly relative to the stationary frame.

A pair of rigid, depending members 66 on opposite sides of the seat are attached by pivots 67 to forwardly extending links 68, the forward ends of which are connected to the upper ends of hangers 69 for footrest 71. The legs 56 are bent in curved portions 72 and are provided on their insides with spaced holes 73. Various means may be employed to latch the footrest relative to the frame. As shown in Figs. 5 and 6 a pin 76 having an enlarged knob 77 on each side of the chair passes through the point of connection between the link 68 and the hanger 69 is biased outwardly by spring 78. By pulling the knobs 77 on the ends of the pins inwardly, the pins 76 may be disengaged from the holes 73 and the position of the footrest 71 adjusted, whereupon springs 78 seat the pins in the proper holes.

Upward movement of the footrest 71 results in rearward movement of the seat 64 by reason of the pivotal connections between the links 68 and hangers 69 and links 68 and depending members 66 on the seat 64.

To adjust the chair shown in Figs. 5 and 6, the pins 76 are pulled inwardly and the footrest 71 raised while at the same time the seat 64 is moved rearwardly from the full line to the dotted line position, whereupon the knobs 77 are released allowing the pins to seat in the new holes. It will be noted that in the modification of Figs. 5 and 6 the links 68 are not connected to the frame.

structure, but on the contrary, are merely pivotally connected to the seat.

In the modification shown in Figs. 7 and 8, still another means of moving the seat rearwardly as the footrest is raised is illustrated. The frame structure of Figs. 7 and 8 provides front and rear legs 81 and 82 which are rigidly connected to horizontal armrests 83 and backrest 84 so that a rigid structure is provided. The seat 86 is suspended from four links 87 of equal length which are pivotally connected to the seat at their lower ends and pivotally connected to the frame structure, in this case the armrest 83, at their upper ends. As the seat 86 is swung rearwardly, it is elevated slightly but the major adjustment of the rearward-swinging movement is the adjustment of the forward edge of the seat relative to the backrest 84.

A footrest 85 is connected to levers 90, the rear ends of which are pivotally connected by transverse rod 88 to the rear legs 82. Links 89 connect the seat 86 to levers 90. Thus, as the footrest 85 is raised and lowered, swinging about rod 88, links 89 swing the seat 86 rearwardly and forwardly.

Various means may be employed to lock the footrest in position. As shown in the accompanying drawings, the upper portions 91 of front legs 81 are curved about pivot points 88 as a center and the inside of the legs are formed with spaced holes 92. A latch means similar to that shown in Figs. 1 and 2 is employed, this latch means being illustrated in Fig. 4.

In the modification shown in Fig. 9, a frame similar to that shown in Figs. 7 and 8 is provided comprising front and rear legs 81 and 82, armrests 83 and backrest 84. Seat 86 is suspended from four links. The two rearmost links 96, on opposite sides of the chair, are pivotally connected to the rear end of the seat 86 and to the rear of the armrest 83. The forwardmost links 97 comprise a U-shape member having a transverse, horizontal base 98, the upper ends of the U being pivotally connected to the forward end of the armrest 83 and the seat being pivotally connected by pivots 99 to the U at a distance spaced downwardly from the top ends thereof equal to the length of rear links 96. Adjacent the lower ends of the vertical portions 101 of the U-shaped link 97 are elongated slots 102. Lever 103 which is pivoted at its forward end to footrest 85 and at its rearward end to rear legs 82 is provided with pins 104 which project through slots 102. Thus, as the footrest is raised the pins 104 slide in the slots 102 and move the lower ends of the U-shaped member 97 rearwardly causing the seat 86 to swing rearwardly. A latching device similar to that shown in Figs. 7 and 8 is provided to latch the footrest to holes 92 in the front legs 81.

Although the foregoing invention has been described in some detail by way of illustration and example for purposes of clarity of understanding, it is understood that certain changes and modifications may be practiced within the spirit of the invention and scope of the appended claims.

What is claimed is:

1. In an adjustable chair, a frame, a backrest mounted on the top of said frame, a seat, means connecting said seat and said frame for movement of said seat relative to said frame, a footrest moveable relative to said frame from a lowered to a raised position, and means connecting said footrest and said seat to move said seat rearwardly as said footrest is raised.

2. In an adjustable chair, a frame, a backrest mounted on the top of said frame, a seat, first means mounting said seat on said frame for forward and rearward movement of said seat while maintaining said seat substantially horizontal, a footrest, second means mounting said footrest on said frame for substantially vertical movement, at least one lever having a first point of pivotal connection with said seat and a second point of pivotal connection with said second means to move said seat and footrest in unison.

said levers being operable to move said first point rearwardly as said footrest is raised.

3. An adjustable chair comprising, a frame, a backrest fixed to said frame, a seat, first means connecting said seat to said frame providing for movement of said seat forwardly and rearwardly relative to said backrest while maintaining said seat substantially horizontal, downwardly extending links connected to said seat, a footrest, second means articulately connecting said footrest with said downwardly extending links, said second means including pivotal connections with said footrest, said second means being connected to said downwardly extending links and said footrest to move the point of connection of said links with said seat rearwardly as said footrest is raised.

4. An adjustable chair comprising a frame, a backrest on said frame, a seat, means mounting said seat on said frame for substantially horizontal sliding backward and forward movement, a footrest, means adjustably securing said footrest to said frame in a plurality of positions of elevation, downward extensions of said seat, and a lever on either side of said chair, each pivotally connected to said footrest at one end and pivotally connected to one of said extensions at the other, the point of connection of said levers to said footrest moving rearwardly as said footrest is raised.

5. A chair according to claim 4 in which said levers are pivotally connected to the rear of said frame and said downward extensions are pivotally connected to said seat.

6. A chair according to claim 4 in which said downward extensions are rigidly connected to said seat.

7. A chair according to claim 4 in which said footrest and said frame are provided with cooperating latch means, the latch means on said frame extending upwardly-rearwardly whereby said levers are moved rearwardly as said footrest is raised.

8. An adjustable chair comprising a frame, a backrest on said frame, a seat, means mounting said seat on said frame for substantially horizontal movement of said seat relative to said backrest, a footrest, a pair of first levers pivotally connected to said frame at their rear ends and connected to said footrest at their forward ends for substantially vertical swinging movement, means latching said footrest and levers in a plurality of posi-

tions of adjustment, and a pair of first links on either side of said chair pivotally connected at their upper ends to said seat and at their lower ends to corresponding levers.

5 9. A chair according to claim 8 in which said seat is mounted for horizontal sliding movement on said frame.

10. A chair according to claim 8 in which said first-named means comprises four second links of equal length pivotally connected at their upper ends to said frame and at their lower ends to said seat.

11. A chair according to claim 10 in which said first links comprise extensions of said second links.

12. An adjustable chair comprising a frame, a backrest on said frame, a seat, four first links of equal length each pivotally connected at one end to said frame and at the other end to said seat for forward and rearward movement of said seat relative to said backrest, a footrest, means for confining said footrest to movement in an upwardly-rearwardly extending path relative to said frame, and second links pivotally connected at one end to said seat and at the other end to said last-mentioned means to swing said seat rearwardly as said footrest is raised.

13. An adjustable chair according to claim 12 in which is further provided a pair of levers pivotally connected at their rear ends to said frame and at their forward ends to said footrest and in which said second links are connected to said levers.

14. An adjustable chair according to claim 13 in which said second links comprise downward extensions of two of said first links and said pivotal connection of said second links and said levers is a sliding connection.
